UNITED STATES PATENT OFFICE.

JOSEPH KEEFE, OF BOSTON, MASSACHUSETTS, ASSIGNOR TO JOHN H. PARKER, OF SAUGUS, MASSACHUSETTS.

SECTIONAL BOX.

1,072,009.

Specification of Letters Patent.

Patented Sept. 2, 1913.

Application filed October 17, 1910. Serial No. 587,609.

To all whom it may concern:

Be it known that I, JOSEPH KEEFE, of Boston, in the county of Suffolk and State of Massachusetts, have invented a new and useful Sectional Box, of which the following is a specification.

My invention relates to boxes consisting of a plurality of sections and the main object of my invention is to provide a box whose sections can be connected without the use of screws, rivets or the like.

Other objects are to provide a simple and efficient sectional box for electrical purposes such as outlet work and to cheapen the manufacture of such boxes.

My invention consists primarily in a box having sections which are connected by members adapted for engagement without the use of screws, rivets or the like.

20 A feature of my invention consists in means for holding the connecting members.

Another feature is the means for holding the outlet closures in position.

Numerous other features will be pointed 25 out below.

In the drawings Figure 1 is a perspective of the separated elements of a box embodying my invention; Fig. 2 is a perspective of the box with the elements assembled; Fig. 3 is a sectional plan of a portion of the box; Fig. 4 is a plan of an outlet box embodying my invention; Fig. 5 is a section on line 5-5 of Fig. 4 looking in the direction of the arrows; Fig. 6 is a section on line 6-6 of Fig. 4 looking in the direction of the arrows; Fig. 7 is a detail of a portion of a partition; Fig. 8 is a detail of portions of two partitions showing the saving of material; Fig. 9 is a broken elevation of a modified form of 30 connecting member; Fig. 10 is a section of the same on line 10-10 of Fig. 9; and Fig. 11 is a plan of the same.

A A' represent sections of my box. Each section comprises a base portion and two 45 side portions a a. From each side portion projections or tongues a' a' a'' a'' extend inwardly crosswise of the box and at right angles to the side portion. These tongues are integral with the side portion and are 50 flat and lie in a vertical plane one above the other. Between the tongues are spaces of about the size of the tongues and at two diagonally opposite corners the top of the tongues are flush with the top of the box 55 while at the other two corners the top tongue

is below the top of the box a distance of one space above referred to. It will be noticed that the vertical plane of the tongues is just outside of the side portion of each section so that when the sections are assembled as 60 in Fig. 2 the tongues a' of one section register with tongues a'' of an adjacent section and all the adjacent tongues are in one vertical plane.

I connect the sections by members mounted to slide down along the juxtaposed tongues and I have shown several forms of these members. In Fig. 1 the form B is a single piece in U-shape of a size to frictionally engage the tongues. In some cases it 65 may not be desirable to rely on friction to prevent movement of the connecting member crosswise of the box and then I may use form B' which is made of a single piece but the U-shaped portions are connected by a 70 portion which extends across the box and which therefore prevents movement of the U-shaped portions crosswise of the box. Form B'' resembles form B' but the central 75 portion is not continuous from the top to 80 the bottom of the box and therefore does not act as a complete partition between the sections which is the case with form B'. It will be observed that my arrangement of 85 tongues and spaces is such that either side of a section will mesh with either side of an adjacent section and this interchangeability is an important feature of my invention.

Although my invention is clearly applicable for use in any situation where it is desirable to connect sections of a box and thereby to make a box of adjustable length, for example, packing strawberry boxes, eggs or other merchandise, yet it has especially 90 practical advantage in electrical outlet work. In such work it sometimes happens that by reason of variation in building construction, or unusual location it is highly desirable to have the apparatus in different sets or in sets of different size, and my invention 95 enables one to carry on such work without the necessity of having at hand a large number of different sizes of boxes because the electrician may readily make a box for his purpose using my elements as occasion may 100 require.

In Fig. 4 I show my invention embodied in an outlet box held in position in a wall or the like by ears D D'. It is desirable to make the parts of outlet boxes of metal and I 110

therefore prefer to make the connecting members with a metal partition portion **E** extending from top to bottom of the box and having riveted to each end metal portions **e** and **e'** to engage the tongues as described above in connection with the other forms of connecting member. The use of a connecting member which is itself a fire-proof partition between adjacent sections is an important advantage of my invention.

At convenient locations I provide outlets **F** which are shown as round holes. Suitably adjacent to the outlets are gibs **f** to engage closures **G** and hold them in place opposite those outlets which are not in use. Each closure is preferably a flat metal plate. These closures are readily slideable so that the outlets may be used for the introduction of conduits. The closures on the bottom of the box are held against movement crosswise of the box by the gibs and against movement lengthwise of the box by a gib on one side and the partition on the other side. Each closure on the sides of the box is held against sidewise movement by a gib on one side and the tongues on the other side. To prevent vertical movement of the closures for the side outlets of the box I prefer to recess the partition as shown at **h** so that the wall of the recess in the partition engages the top of the closure and holds it against vertical movement.

When a closure at the bottom of the box is to be removed the partition is slid upward partially or wholly and the closure may then be slid lengthwise of the box. When a closure is to be removed at the side of the box in the preferred form the partition must be wholly removed and then the closure may be readily slid out vertically along the side of the box. In Fig. 7 I have shown a detail of the recessed partition and in Fig. 8 I have illustrated the saving of material due to this recessing. From this figure it will be clear that cutting the recess of member **e** furnishes the projection of member **e'** and vice versa with the result that in cutting the two members **e** and **e'** a strip of material of the depth of the recess is saved. I may use as a connecting member the form **B** shown in Figs. 9, 10 and 11 which is made in a single piece with one set of tongues **b** in a vertical plane at one side of the main portion of the connecting member and with another set of tongues **b'** alternating with the first set and in another plane at the other side of said main portion. The tongues of this member **B** will engage the appropriate tongues of the sections and thereby hold the latter together.

In assembling my box as many sections as desired are placed side by side with the adjacent projections or tongues in line, and the connecting member is then slid downwardly over the tongues and the box is com-

plete. When it is desired in electrical work to use an outlet at the bottom of the box the adjacent partition or end wall, the end connecting member being in reality the end wall of the box, is slid up as far as desired and the closure of that outlet is slid out endwise of the box. When an outlet in the side of the box is to be used the partition or end wall is entirely removed and the closure for that outlet is slid upward out of the box and the partition is then replaced.

Among the many advantages of my box I may call attention to the simplicity of construction, the few steps necessary in its construction, the saving of material and cheapness. An important advantage is that no screws or the like are necessary to connect the sections and the interchangeability of the parts is also important. Another advantage is that the joints are all within the box.

What I claim is:

1. A sectional box comprising several sections each having a plurality of integral projections, and a member to engage a plurality of projections of one section and also a plurality of projections of an adjacent section and hold those sections together, said member being slidably mounted externally on the projections which it engages.

2. A sectional box comprising several sections each having a plurality of tongues at right angles to the side of the section and a member separate from the sections to engage a plurality of tongues of one section and also a plurality of tongues of an adjacent section and hold those sections together, said member being slidably mounted on the projections which it engages.

3. A sectional box comprising several sections each section having a projection and a member slidably mounted externally on the projections of adjacent sections to hold those sections together.

4. A sectional box comprising several sections each section having a projection at opposite sides; and a member consisting of three portions, one portion to engage adjacent projections at one side of the sections to hold that side together, another portion to engage adjacent projections at the other side of the sections and hold that side together and a third portion connecting the other two and holding one of them in engagement with the projections at one side of the sections and the other in engagement with the projections at the other side of the sections, said member being slidably mounted on the projections which it engages.

5. A sectional box comprising several sections each having a tongue, the tongues of adjacent sections being in line, said line being at a right angle to the bottom of the box; and a member to externally engage the tongues of adjacent sections and hold those sections together.

6. A sectional box comprising several sections each section having two projections opposite each other and a member having a portion slidably mounted on the adjacent 5 projections of adjacent sections at one side of the box and having another portion slidably mounted on the adjacent projections of adjacent sections at the other side of the box and having a third portion rigidly connecting said two other portions. 10
7. A sectional box comprising several sections and a partition of fireproof material to hold the sections together, the partition extending from one side of the box to the 15 other.
8. In a box of the character described the combination of several sections each section having outlets; closures for the outlets; and means which hold the sections together and which also hold the closures in position with 20 relation to the outlets.
9. In a box of the character described the combination of several sections; outlets in the sections; a partition between adjacent 25 sections; and closures for the outlets held in place by the partition.
10. A sectional box comprising several sections, each section having a plurality of vertical tongues, the tongues of one section 30 alternating with those of the adjacent section and all the adjacent tongues of adjacent sections being in line; and means to engage the tongues externally and thereby hold the sections together. 35
11. In a box of the character described the combination of several sections, each section having a plurality of tongues, the tongues of one section alternating with the adjacent ones of the adjacent section; and a member having alternately-arranged projections to engage said tongues and thereby hold adjacent sections together. 40
12. A sectional box comprising several sections each having a projection near the edge of its side wall and at right angles to 45 said wall; and a member slidably mounted on the projections of adjacent sections to hold said sections together.
13. A sectional box comprising several sections each section having a projection; 50 and a member within the box but mounted externally on the projections to hold adjacent sections together.
14. In a box of the character described the combination of several sections, one of 55 said sections having an outlet; a closure for said outlet; and means which hold the sections together and which also hold the closure in position with relation to the outlet. 60
15. In a box of the character described the combination of several sections, one of said sections having an outlet; a partition between adjacent sections; and a closure for said outlet held in place by the partition. 65
